1

This invention relates to improvements in driving mechanism for the tube frame conveyor systems of Axminster looms.

Axminster looms ordinarily operate with a large number of tube frames which move one at a time to a transfer station. Part of the mechanism for moving the tube frame system includes a pullover shaft which rocks periodically to place the tube frames in position for detachment from the chains by a transfer arm. The pullover shaft generally moves at least part of the system by power derived from the loom driving motor. It is an important object of the present invention to provide a separate motor running continuously during loom operation to move the entire tube frame conveyor system.

Heretofore the pullover shaft has been given its periodic angular motions by pawls and ratchets which are not as accurate as is desired in their movements. It is another object of the invention to secure greater accuracy in the turning of the shaft by the use of a Geneva movement including a star wheel which moves with the shaft and a pin wheel which turns during loom operation.

It is necessary to provide some means for locking the pullover shaft against rotation during the time a tube frame is detached from the system. In the past strong brakes have been applied to the pullover shaft for this purpose, and releasers have been necessary to open the brakes to permit rocking of the shaft. It is difficult, however, to time the releasers so they will open the brakes at the right time relatively to rocking of the pullover shaft, and the loom, or motor for the system, is required to start movement of the shaft while the brakes are still on. It is an important object of the present invention to provide a Geneva movement which will rock the pullover shaft periodically and lock the shaft between successive rockings thereof, but unlock the shaft at the start of a rocking movement of the pullover shaft.

When a motor drives the entire conveyor system it must present the tube frames to the transfer station at a rate coordinated with the rate of operation of the loom. It is another object of the invention to provide timer means to keep the motor in step with the loom.

In narrow Axminster looms in which the tube frames are short the system can be moved periodically throughout its length, and when the present invention is applied to such looms the pin wheel of a Geneva motion supplies the power to move all of the conveyor system. In wider looms utilizing tube frames of much greater length the conveyor system attains a considerable weight and it

is desirable to move the greater part of the system continuously and move only a small part of it periodically. When applying the present invention to such looms the motor will have two driving connections for the conveyor system, one providing the periodic movement for the small part of the system and the other providing the continuous movement for the greater part of the system.

One type of Axminster loom which has gone into extensive use is so constructed that the pullover shaft rocks through about $\frac{1}{5}$ of the three-pick cycle of the loom when the latter is operating three-shot. When the present invention is applied to such looms I find it desirable to employ eccentric or elliptical gearing between the driving motor and the pin wheel of the Geneva motion so that the pin wheel will rock the pullover shaft in about $\frac{1}{5}$ of a three-pick cycle of the loom. It is to be understood, however, that certain features of the invention are not limited to such looms.

It is necessary in the weaving of certain patterns to be able to reverse the conveyor system, preferably when the pin wheel is not moving the star wheel. Since the pin wheel will have a considerable amount of idle angular movement the reversal may occur either when the pin wheel has just left the star wheel, or is about to engage it. These two positions will represent different amounts of angular movement of the pin wheel and its driving motor with respect to the loom and a reversal might be accompanied by a loss of time between the pin wheel and the loom such that the first rocking of the pullover shaft after reversal would not occur at the correct point in the loom cycle. It is another object of the present invention to provide clutch means forming part of the reversing mechanism which will insure proper timing of the Geneva movement with respect to the loom when reversed regardless of the amount of idle angular movement of the pin wheel after its last operation of the star wheel.

From time to time it is necessary to remove the spent tube frames and replace them with a new set with fully wound spools while the loom is idle. Movement of the conveyor system under these conditions is effected by the electric motor, but upon completion of the insertion of a new set of tube frames the pin wheel and motor which drives it should be connectible to the loom in the same angular or timed relation which existed during the previous loom operation. In order to accomplish this result it is a further object of the present invention to provide clutch means between the aforesaid timer and the loom so constructed that the timer and therefore the motor and pin

wheel can be re-connected to the loom at one point only in the three-pick cycle, that point being correct for the resumption of weaving.

With these and other objects in view which will appear as the description proceeds, my invention resides in the combination and arrangement of parts hereinafter described and set forth.

In the accompanying drawings, wherein two forms of the invention are shown:

Fig. 1 is a side elevation of an Axminster loom as viewed from the left end thereof having the preferred form of the invention applied thereto in such manner that the Geneva movement moves the entire chain periodically, 10

Fig. 2 is an enlarged side elevation of the Geneva movement and associated parts shown in Fig. 1, 15

Fig. 3 is a plan view partly in section looking in the direction of arrow 3, Fig. 2,

Fig. 4 is a front elevation looking in the direction of arrow 4, Fig. 2, showing the reversing mechanism for the pullover shaft, 20

Fig. 5 is an enlarged vertical section on line 5-5 of Fig. 3,

Fig. 6 is a diagrammatic view showing the pin and star wheel with the latter locked by the pin wheel, 25

Fig. 7 is a detailed plan view looking in the direction of arrow 7, Fig. 1,

Fig. 8 is an enlarged vertical section on line 30 8-8 of Fig. 7 showing the clutch which connects the timer with the loom, and

Fig. 9 is a view similar to Fig. 1 but showing the modified form of the invention applied to a loom having a heavy tube frame conveyor system part of which is driven periodically and part of which is driven continuously by the driving motor.

Referring to Fig. 1, a conventional narrow Axminster loom is designated at L and includes a bottom shaft 10 driven by a loom motor LM and completing a rotation thereof each three picks of the loom when the latter is weaving three-shot fabric. A number of mechanisms not germane to the present invention are operated by cams and the like on shaft 10, one of these mechanisms being transfer arms well known but not set forth herein. It is thought sufficient for present purposes to state that every third pick of the loom a tuft forming operation will occur, and at this time a tube frame must be in position to be moved to tuft forming position.

The tube frame conveyor system is designated generally at CS, and since the application of the invention as contemplated in Fig. 1 is to a loom in which the system CS will be comparatively light, said system may be tight throughout its length and have its endless chains 11 trained over several guide sheaves or pulleys 12 and under a pullover shaft 13. The latter is suitably supported by the loom and its general function may be as usual, that is, it rocks periodically to advance the chains 11 to move tube frames 14 one by one to a transfer station S under shaft 13. System CS may be mounted on a frame F supported in part by the loom and in part by uprights 15.

The matter thus far described is somewhat similar to looms of corresponding types heretofore proposed, but in these previous looms the pullover shaft has been given periodic movements by power derived from the loom motor LM. In the present instance the entire conveyor system CS is moved by power derived from a conveyor motor CM running continuously during loom

operation and suitably mounted on a stand 20 supported by the loom. This motor may have a reversible built-in gear reduction unit not shown having an output shaft 21 which will complete a rotation every third pick of the loom when the latter is operating three-shot.

Shaft 21 has secured thereto an elliptic gear 22 which meshes with a second elliptic gear 23 secured to a short shaft 24 suitably mounted for rotation on the loom frame. As shown in Fig. 3 that end of shaft 24 adjacent to the motor CM has secured thereto a pin wheel 25 having an operating pin 26 and a locking surface 27 concentric with shaft 24, see Fig. 6.

The pullover shaft 13 is driven by a star wheel 30 which cooperates with the pin wheel and in the present instance is shown as provided with six pin receiving slots 31 and six locking surfaces 32 of the same radius as the lock 27 of the pin wheel. The star wheel is loose on the pullover shaft and turns with a bevel gear 33 meshing with a second bevel gear 35 rotatable on a stud 37 turning in a bearing 38 secured as at 39 to the loom frame. Bevel gear 36 meshes with a third bevel gear 40 also loose on shaft 13.

A clutch 41 keyed to shaft 13 is slideable along the latter so that it can be clutched to either of the bevel gears 35 or 40, one at a time. The clutch is under control of an arm 43 rocking about a pivot 44 supported by the loom, see Fig. 4. The clutch can assume a neutral position in which it is out of driving relation with either of the bevel gears 35 or 40, but in normal loom operation it will be operatively connected to one or the other of these two bevel gears.

A motor CM tends to turn shaft 21 slightly faster than one revolution for each three picks of the loom, but is prevented from doing so by a timer mechanism designated generally at T. 40 This mechanism may include a sprocket wheel 45 secured to shaft 21 and meshing with a timing chain 46 trained over idler sprockets 47 and 48 and meshing with a sprocket wheel 49 supported by the main bottom shaft 10 of the loom, see Fig. 7. Sprocket wheel 49 is formed with a clutch member 50 having a tooth 51 and a recess 52 for meshing respectively with a recess 53 and tooth 54 of a second clutch member 55 keyed to and slideable along shaft 10. Clutch member 50 can be operatively connected to clutch member 55 in only one angular position of sprocket wheel 49 relatively to shaft 10.

Clutch member 55 may be controlled by a lever 56 pivoted with respect to the loom at 57 and having a rod 58 leading to a handle 59, see Figs. 1 and 7. During normal loom operation handle 59 will be in such position as to cause clutch members 50 and 55 to mesh with each other, but when a new set of tube frames is to be applied to the conveyor system CS the handle 59 will be moved to its abnormal position to disconnect the clutch members 50 and 55, thereby permitting the motor CM to run independently of the loom. When weaving a heading between rugs clutch members 50 and 55 may be separated and motor CM stopped, or clutch 41 can be moved to neutral position.

In the operation of the matter thus far described it may be assumed that shaft 10 turns 70 counterclockwise, Fig. 1, clutch 41 is clutched to bevel gear 35, and the conveyor system CS is moving in a forward direction as indicated by arrow a in Fig. 1. Shaft 24 will be turned in a clockwise direction as viewed in Fig. 1 by the motor CM 75 and the pin of the pin wheel will enter the star

wheel slots 31 successively to give the pullover shaft 13 periodic rocking movements in a counterclockwise direction occurring at three-pick intervals. During the active part of the rotation of the pin wheel when it is moving the star wheel the lock surface 27 is in non-locking relation with respect to the star wheel, but upon completion of the angular movement of the star wheel by the pin wheel, and during the idle part of the rotation of the pin wheel, said surface 27 will engage one or the other of the concave surfaces on the star wheel and lock the latter and therefore the pullover shaft against angular movement. This locking dispenses with the brakes already mentioned hereinbefore. If desired, however, a light weight brake can be used, but it will not be nearly as strong as those used heretofore. When the system CS is reversed the motor CM and the Geneva movement will continue to turn as previously, and reversal of shaft 13 will be effected by shifting clutch 41 out of driving relation with respect to bevel gear 35 and into driving relation with bevel gear 40. The conveyor system will then move in the direction opposite to that indicated by arrow *a*, Fig. 1. Since the conveyor system including the tube frame transporting chains is tight throughout its length it will be moved in its entirety by the pin wheel, and the timer means T will require the movements of the pullover shaft to be coordinated with the other parts of the loom.

When reversing the direction of movement of the system CS it is necessary to maintain the correct time relation between the star wheel and the loom. This result I accomplish by forming each end of the clutch 41 with six teeth 60 of the same width equally spaced by recesses 61, and forming the bevel gears 35 and 40 with similar teeth and recesses. The reversal will ordinarily occur after the last rocking of the pullover shaft and star wheel for a given direction of movement of the system CS. The star wheel will therefore be locked by the locking surface 27 of the pin wheel, and since it is locked the bevel gears and clutch 41 and pullover shaft 13 will also be locked, but the clutch teeth on the bevel gears 35 and 40 will be opposite their recesses 61 on the clutch and the latter can therefore be shifted from operative relation with respect to one bevel gear, such as 35, into operative relation with respect to the other bevel gear 40 without loss of angular time between the pullover shaft and the star wheel. The star wheel always turns in the same direction and the clutch 41 is between the star wheel and the pullover shaft.

The invention has been set forth herein as more particularly adaptable to the type of Axminster loom which has gone into general use and wherein the rocking of the pullover shaft occupies about $\frac{1}{5}$ of the time of a three-pick cycle of the loom. In order that the pin wheel may complete its rocking of the star wheel within this $\frac{1}{5}$ of three picks and at the same time preserve correct operating relations between the pin wheel and the star wheel, the degree of ellipticity of gears 22 and 23 is such as will cause the pin wheel to give the star $\frac{1}{6}$ of a turn in $\frac{1}{5}$ of three picks. The effect of the elliptic gears is to make the pin wheel move somewhat faster than its average rate of movement when driving the star wheel, and there will be a corresponding retardation in its rate of movement of the pin wheel during its period of idleness with respect to the star wheel. It will be noted that the pin wheel turns at a variable rate even though the timer chain

46 moves at a uniform rate, and it will also be noted that the reversing mechanism including the bevel gears 35, 36 and 40 permit the motor to run always in the same direction as required by the timer.

In the modified form of the invention shown in Fig. 9 the greater part of the mechanism thus far described in connection with Figs. 1 to 8 may be utilized, but instead of driving the entire modified chain or conveyor system CS' directly from the pullover shaft part of the system is driven at a constant rate by power derived from the motor CM. As shown in Fig. 9, the conveyor system CS' comprises chains 70 for the tube frame and has a framework F' supporting a relatively long horizontal shaft 72 provided with worms 73, 74, 75 and 76. These worms mesh with worm wheels 77, 78, 79 and 80. Sprocket wheels 81 in driving relation with the chains 70 turn with the worm wheels and during rotation of shaft 72 effect driving of the greater part of the conveyor system, designated herein at TS and extending from worm wheel 78 to the left around wheels 79 and 80 and then to the right around wheel 77.

Another section PS of the conveyor system extends around the pullover shaft and its upper part meshes with idler sprocket wheels 85 and 86 caused to turn with each other and in the same direction by a coordinating chain 87. A third idler sprocket 88 is located to the left of idler sprocket 86 as viewed in Fig. 9. The sections PS and TS are tight and are connected by front and back wells W' and W2 which are formed by slack sections of the conveyor system CS'. The part of the conveyor system shown in Fig. 9 thus far described may be of common construction and of itself forms no part of my present invention.

In order that shaft 72 may be driven by power derived from motor CM the latter is provided with a bevel gear 90 meshing with a bevel gear 91 secured to the lower end of an upright shaft 92 the upper end of which has secured thereto a driving bevel gear 93. The latter meshes with right and left bevel gears 94 and 95 which are freely rotatable on shaft 72. A clutch 96 similar to clutch 41 is keyed to shaft 72 and slidable therealong to have driving relation with one or the other of the bevel gears 94 or 95 one at a time.

Sliding of clutch 96 is accomplished by means of a reversing lever 97 connected by a link 98 to lever 43. The reversing mechanism comprising clutch 96 and the bevel gears 93, 94 and 95 are similar in construction and operation to the reversing mechanism already described in connection with Fig. 3, and it is thought a more detailed description of them is not necessary. Link 98 is shown as connected to lever 43 in Fig. 4, but it will not be thus connected in the preferred form of the invention.

In the modified form of the invention the section TS of the conveyor system will be much heavier and longer than the section PS and it will be driven at a constant rate by the motor acting through shaft 92 and clutch 96. The motor will also operate the pin and star wheel mechanism which may be the same as that described for the preferred form of the invention, hence section PS will move periodically. By having the greater part of the conveyor system CS' moved constantly a smaller motor CM can be employed than would be required if the entire system were moved periodically throughout its length.

From the foregoing it will be seen that I have

provided improved driving means for the pullover shaft of an Axminster tube frame conveyor system wherein a constantly running motor CM moves the entire system. Both forms of the invention utilize a Geneva movement including a star wheel operatively connected to the pullover shaft and a pin wheel which turns constantly under control of the loom. The pin wheel is shown herein as being driven by a motor, but I am not limited to a motor as an actuator for turning the pin wheel. The Geneva movement is made with a lock which prevents turning of the pullover shaft during the idle part of the rotation of the pin wheel. This locking eliminates the heavy brakes previously used on the pullover shaft. Furthermore, the timer T limits the speed at which the motor can turn the pullover shaft and therefore coordinates the movements of the star wheel with the loom. It will also be seen that the pullover shaft can be reversed even though the motor, the pin wheel and the star wheel always turn in their same respective directions. Also, when the pullover shaft is reversed the star wheel and bevel gears associated with it will be stationary and since the number of teeth on clutch 44 is the same as the number of slots in the star wheel, the clutch can be shifted without loss of angular time between the star wheel and the pullover shaft. The elliptic gears 22 and 23 cause the pin wheel to turn faster than its average rate when driving the star wheel. Also, the clutches 50 and 55 prevent the pullover shaft driving mechanism from being timed with the loom in any position except the correct one in which star wheel movements will be properly timed with respect to the loom. Furthermore, in the modified form of the invention, a single driving motor for the entire conveyor system drives a part of the latter at a constant rate and drives another part thereof periodically.

Having thus described my invention it will be seen that changes and modifications may be made therein by those skilled in the art without departing from the spirit and scope of the invention and I do not wish to be limited to the details herein disclosed, but what I claim is:

1. In an Axminster loom having a driving motor and provided with a tube frame conveyor system having two tight sections connected by two slack sections, a second motor for the conveyor system separate from the driving motor, mechanisms operatively connecting the second motor to said tight sections and effective to cause said second motor to move one tight section periodically and move the other tight section continuously, and timer means controlled by the driving motor regulating the rate of running of the second motor.

2. In an Axminster loom having a driving motor and provided with a tube frame conveyor system having a tight section moved by a pullover shaft and having another tight section movable independently of the first tight section, a second motor running continuously during loom operation, operative connections between the second motor and the first tight section moving the latter periodically during loom operation, other operative connections between the second motor and the other tight section moving the latter continuously during loom operation, and timer means controlled by the driving motor regulating the rate of running of the second motor.

3. In an Axminster loom having a tube frame conveyor system part at least of which is moved step-by-step when a pullover shaft has periodic

angular movements, a star wheel operatively connected to and turning with the pullover shaft, and a pin wheel to move the star wheel rotating at a rate which varies during a rotation thereof and causing angular movement of the star wheel and the pullover shaft when turning at the faster rates thereof.

4. In an Axminster loom having a pullover shaft operatively connected to a tube frame conveyor system, a Geneva movement including a star wheel operatively connected to the pullover shaft and a rotary pin wheel to move the star wheel, an actuator to turn the pin wheel during loom operation, and elliptic gearing operatively connecting the actuator and pin wheel causing the latter to have a higher average rate of angular motion when moving the star wheel than the average rate of angular motion of the pin wheel during a complete rotation thereof.

5. In an Axminster loom having a pullover shaft operatively connected to a tube frame conveyor system, a Geneva movement including a star wheel operatively connected to the pullover shaft and a rotary pin wheel to move the star wheel, and actuator means for the pin wheel causing the latter to have a higher average rate of turning when moving the star wheel than the average rate of turning of the pin wheel during a complete rotation thereof.

6. In an Axminster loom having a pullover shaft operatively connected to a tube frame conveyor system and effective due to periodic movements thereof to cause a step-by-step movement of that part of the system operatively connected to the pullover shaft, a Geneva movement including a star wheel operatively connected to and turning with the pullover shaft and the latter being stationary when the star wheel is stationary, a rotating pin wheel for the star wheel causing the star wheel and pullover shaft to move angularly during a given part only of a rotation of the pin wheel, and actuator means for the pin wheel causing the latter to move at a faster angular rate during said given part of a rotation thereof than during the remainder of the rotation thereof.

7. In an Axminster loom turned always in the same direction during operation, the loom having a tube frame conveyor system movable forwardly or reversely during loom operation, a motor turning always in the same direction during loom operation, a Geneva movement having pin and star wheels driven by the conveyor system motor and turning always in their same respective directions during loom operation, and reversible driving connections operatively connecting the star wheel and conveyor system.

8. In an Axminster loom turned always in the same direction by a driving motor during loom operation, the loom having a tube frame conveyor system movable forwardly or reversely during loom operation, a conveyor system motor, timer means operatively connecting the loom and conveyor system motor and requiring the latter always to turn in the same direction during loom operation, a pin wheel rotated by the conveyor system motor, a star wheel turned angularly periodically by the pin wheel, and reversible driving connections operatively interposed between the star wheel and conveyor system.

9. In an Axminster loom turned always in the same direction during operation, the loom having a tube frame conveyor system movable forwardly or reversely during loom operation, and includ-

ing two sections to be driven, a motor to drive both sections turning always in the same direction during loom operation, a Geneva movement actuated by the motor, reversible driving connections between the Geneva movement and one of said sections driving the latter periodically either forwardly or reversely, and reversible driving connections between the motor and the other section driving the latter continuously either forwardly or reversely.

10. In an Axminster loom having driving means and a pullover shaft operatively connected to part of a tube frame conveyor system, a star wheel turning with the pullover shaft, a pin wheel for tuning the star wheel, a motor running continuously during loom operation, elliptic gearing operatively connecting the motor and the pin wheel causing the latter to turn at a variable rate with respect to the speed of the motor and effect movement of the star wheel and pullover shaft by the pin wheel at a rate above the average rate of the pin wheel, and timing means controlled by said driving means moving at a uniform rate operatively connected to the motor causing the latter to run at a uniform rate while the pin wheel turns at a variable rate.

11. In an Axminster loom having driving means and a pullover shaft operatively connected to a part of a tube frame conveyor system, a star wheel secured to and turning with the pullover shaft, a pin wheel for the star wheel, a motor running continuously during loom operation, an elliptic gear turning with the motor, a second elliptic gear meshing with the first gear turning with the pin wheel, said elliptic gears effective to cause the pin wheel when turning the star wheel

to turn the latter at a rate greater than the average rate of the pin wheel, and timing means between said driving means and the motor requiring the motor to run at a uniform rate when the pin wheel is turning said star wheel.

12. In an Axminster loom having driving means and a pullover shaft operatively connected to part of a tube frame conveyor system, a star wheel connected to and turning with the pullover shaft, 10 a pin wheel for the star wheel, a motor running continuously during loom operation, a timing chain operatively connecting said driving means and the motor requiring the motor to run at a uniform rate, and elliptical gearing operatively 15 connecting the motor and the pin wheel effective to drive the latter at a rate variable with respect to the rate of said driving means and motor and cause the pin wheel to turn the star wheel and pullover shaft at a rate greater than the rate of the motor.
